W. L'HOMADIEU & J. L. BRUMFORD,

FAN SUPPORT.

APPLICATION FILED MAY 11, 1917.

1,263,442.

Patented Apr. 23, 1918.

Attorney

UNITED STATES PATENT OFFICE.

WALTER L'HOMADIEU, OF ONEIDA, AND JAMES L. BRUMFORD, OF CANAJOHARIE,
NEW YORK.

FAN-SUPPORT.

1,263,442.

Specification of Letters Patent. Patented Apr. 23, 1918.

Application filed May 11, 1917. Serial No. 167,974.

To all whom it may concern:

Be it known that we, (1) WALTER L'HOMADIEU and (2) JAMES L. BRUMFORD, citizens of the United States, and residents 5 of (1) Oneida, in the county of Madison and State of New York, and (2) Canajoharie, in the county of Montgomery and State of New York, have invented certain new and useful Improvements in Fan-Supports, of 10 which the following is a specification.

This invention relates to new and useful improvements in fan supports, and the primary object of the invention is the provision of a new and improved supporting 15 device whereby electric fans of the conventional type, are adapted to be supported at any desired angle, and to be detachably connected with the conventional type of electrical fixture, drop cord or bracket as de- 20 sired.

Another object of the invention is to provide a device of this character which is easily and simply constructed, inexpensive to manufacture, and one which will be very 25 efficient in operation.

With these and numerous other objects in view our invention consists of the novel features of construction, combination and arrangement of parts which will be herein 30 referred to and more particularly pointed out in the specification and claims.

In the accompanying drawings:

Figure 1 is a top plan view of the attachment showing the same applied to the 35 conventional type of electric fan, and

Fig. 2 is a detailed perspective view of the bracket.

In describing our invention we shall refer to the drawings in which similar reference 40 characters designate corresponding parts throughout the several views.

The numeral 1 designates an electric fan of the conventional type, that is provided with a motor 2 adjacent one side thereof; 45 and the usual form of frame 3 that forms a guard for the blades of said fan. Our new and improved supporting device includes a bracket 4, that is formed from a substantially U-shaped strip of metal having a longitudinally extending slot 5 therein, and the opposite ends of said strip are bent inwardly toward each other, and are secured 50 to the inner side of the motor 2 as clearly shown in Fig. 1 of the drawings.

The attaching means employed in this device includes a tubular member 6 having its inner end externally threaded as shown at 55 7, and said end being adapted to be positioned in the slot 5, and clamped to the bracket 4 by means of a pair of clamping nuts 8 disposed on opposite sides of said bracket, on the end of the member, whereby the said member is adapted to be adjustably connected with said bracket for a purpose 60 which will be hereinafter more fully de- 65 scribed.

Secured within the outer end of the bracket 6 is a conventional type of attaching plug 9, and extending therefrom through the tubular member 6 and bracket, and connected with the motor 2 are a pair of current conducting wires 10.

In operation the tubular member 6 is adapted to have its outer end 9, in which the plug is positioned connected with the 75 conventional type of electric light fixture, or drop cord, and owing to the fact that the bracket 4 is adjustably connected with the outer end of said member, it is obvious that the fan may be adjusted to any desired 80 angle. The plug 9 is connected by wires 10 with the motor 2, so that current may be carried thereto, to operate the fan, when the support is in position.

This device forms a simply constructed 85 and economically manufactured fixture, for securely holding an electric fan in various adjusted positions, and connecting the same with the conventional type of electric light fixture. The device is extremely simple in 90 construction, and is readily applicable to the conventional type of electric fans in common use. The inner ends of the bracket 4 may be secured to the motor by any desired means, either riveting, as shown in the 95 accompanying drawings, or detachably connected therewith if desired.

From the foregoing description, taken in connection with the accompanying drawing, the advantages of the construction and of 100 the method of operation will be readily apparent to those skilled in the art to which the invention appertains, and while we have described the principle of operation of the invention, together with the device which 105 we now consider to be the best embodiment thereof, we desire to have it understood that the device shown is merely illustrative, and

that such changes may be made when desired as are within the scope of the claims appended hereto.

Having fully described our invention, 5 what we claim as new, and desire to secure by Letters Patent, is:

1. The combination with an electric fan having a motor, of a substantially U-shaped bracket secured to said motor, said bracket 10 having a slot therein, a tubular supporting member having its free end positioned through said slot, means for releasably connecting said end of the member to the bracket, a plug in the other end of said member, and current conducting wires extending from said plug through the member to the motor.

2. A device of the class described including a substantially U-shaped bracket having its ends adapted to be connected to an 20 electric fan, said bracket having a longitudi-

nally extending slot therein, a tubular supporting member having one end positioned in said slot, and clamping nuts on said end to secure the same to the bracket in various 25 adjusted positions.

3. A device of the class described including a substantially U-shaped bracket having its ends adapted to be connected to an electric fan, said bracket having a longitudinally extending slot therein, a tubular supporting member having one end positioned in said slot, clamping nuts on said end to releasably secure the same to the bracket, a plug in the opposite end of said member, and an electrical connection between the same and the fan motor extending through said member. 30 35

In testimony whereof, we affix our signatures hereto.

WALTER L'HOMADIEU.
JAMES L. BRUMFORD.
